UNITED STATES PATENT OFFICE.

PATRICK J. LUCEY, OF CHICAGO, ILLINOIS.

KNIFE GUARD FOR SLICING MACHINES.

Application filed February 17, 1922. Serial No. 537,297.

To all whom it may concern:

Be it known that I, PATRICK J. LUCEY, a citizen of the United States, and a resident of the city of Chicago, county of Cook, and 5 State of Illinois, have invented certain new and useful Improvements in Knife Guards for Slicing Machines, of which the following is a specification.

My invention relates to new and useful 10 improvements in knife guards for slicing machines, and has for its object the provision of guard means for the entire edge of the knife, including the near or slicing portion of said edge.

15 The slicing machines on the market are usually provided with guard means for covering the upper portion and far portion of the knife, leaving the inner or slicing portion of the knife exposed, and some of the 20 machines are provided with means for guarding the slicing portion by the use of a member placed outward and at the side of the cutting edge of the knife, usually a bent wire, such member or wire being placed sufficiently sideways to permit a slice to be cut 25 with the knife while said member remains in position; but such guards do not extend completely over the cutting portion of the knife edge to effectively cover the same; and 30 with the addition of such wire or member to the former type of guard, such combined guards are not sufficient to prevent injury to the part of the body advanced to the knife edge from the concave side of the knife and 35 dangerous accidents frequently result from the lack of guard means for effectively covering the cutting portion of the knife edge. It has also been proposed to cover the cutting portion of the knife edge by a means 40 which is circularly slidable over the old form of guard means at the top and far portion of the knife, in order to uncover the knife edge, and is slidable over the cutting portion to cover the same, but this circularly 45 slidable or telescopic means is actuated by hand requiring constant attention, and is therefore entirely impractical.

It is my main object to avoid such unfortunate accidents and inconvenience as 50 pointed out above; and to provide guard means for fully and effectively covering the slicing portion of the knife edge, as well as the remaining portions.

It is my further object to provide the 55 guard means with a movable part for the slicing portion of the knife edge, and pro-

vide means automatically actuated by the machine for moving said part to uncover said portion of the knife during the effective slicing movement, and to again cover 60 said portion during the reverse movement.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side elevation of the knife and 70 of my improved guard mounted in position thereon,

Fig. 2 is an end elevation of the guard, 75 Fig. 3 is an enlarged vertical section on line 3—3 of Fig. 1,

Fig. 4 is an enlarged vertical section on line 4—4 of Fig. 3, and

Fig. 5 is a horizontal section on line 5—5 of Fig. 2.

In the drawing I have shown a portion of 80 the frame 10 of a well-known type of slicing machine provided with a movable table 11 and a supporting plate 12 movably mounted on said table. A knife 13 is rotatably mounted on a supporting bracket 14 provided on 85 the upper end of a housing 15 extending from said frame.

The guard for the knife comprises a curved member 18, substantially semicircular in cross section, which covers and guards 90 the upper and the far portion of the knife edge and is held in position by means of upper brackets 19 and 19', fastened to the upper part of the housing 15, and a bracket arm 20 fastened to the lower part of said 95 housing, in any suitable manner. To the above guard I also add a stationary guard for the cutting portion of the knife edge, in the form of a curved rod 21 positioned slightly outwardly from the edge of the 100 knife and on the convex side thereof, and fastened at its upper end on the bracket arm 19 by means of a member 22, or in any convenient manner, and mounted at its lower end 23 on a bracket 24 attached to the housing 15. Both of the above guards are retained fixed in position.

In addition to the stationary guard means so far described, I provide a movable or swingable guard means for fully and effectively covering the cutting portion of the 110 knife edge, which means comprises a curved

member 25 preferably semicircular in cross section which is provided at its upper end with a laterally extending arm 26 pivotally mounted in a lug 27 attached to the bracket 19, and is provided at its lower end with a corresponding arm 28 pivotally mounted in the bracket 24.

I provide means for automatically operating the movable guard, such means comprising a lug 29 which extends horizontally from the lower end of the guard 25 and is provided with a slot 30. A pivot pin 31 is movably positioned in said slot and is fastened to the flattened end 32 of a reciprocating plunger 33 which is longitudinally movable through an opening 34 in the frame 10. A bracket 35 is mounted in frame 10, near the opening 34 and knife 13, and a shaft 36 is rotatably mounted in the lower part of said bracket. A bevel gear 37 is adjustably fastened on one end of shaft 36, as with a set screw 38, and meshes with a bevel pinion 39 adjustably fastened on the usual driving shaft 40 of the slicing machines, and a washer 41 is fastened on the opposite end of said shaft by means of a pin 42 or in any suitable manner. The bevel gear 37 is provided with a cam flange 43 half way around its rear face, and the plunger 33 has a bearing shoe 44 adjustably mounted at its inner end, by a set screw 45 and a stem 46 and sleeve 47 on the plunger and shoe, or by any means suitable to adjust the shoe for wear. A spring 49 bears with one end against the inner wall of a chamber 50 provided in the bracket 35, and with the other end against the collar 51 mounted on the plunger 33 to constantly urge the shoe 44 against the rear face of the bevel gear 37 and cam flange 43.

In operation, as the driving shaft 40 is being actuated by the usual crank wheel (not shown) or other driving means, the pinion 39, fastened on said shaft rotates the gear 38. The number of teeth on the gear and on the pinion are so arranged that the gear makes one complete revolution during the time that the supporting table 11 makes one complete round of its to and fro motion with respect to the knife 13, and since the driving shaft 40 of the usual slicing machine makes two revolutions during the complete round or to and fro motion of the table, the ratio of teeth on the gear 38 and pinion 39 is 2 to 1. The movable guard and operating mechanism therefor is so adjusted when I mount the same and while I fasten the pinion on the driving shaft, that during the slicing stroke of the machine or while the table 11 and plate 12 move toward the knife, the cam 43 engages the shoe 44 and moves the plunger 33 outward, thereby moving the lug 29 and swinging the attached guard 25 on its pivoting arms 26 and 28, away from the knife edge, into the position shown in

dotted lines in Fig. 2, thus clearing the cutting portion of said edge during the cutting or slicing stroke of the machine, and while the table makes its return movement cam 43 passes from under shoe 44 permitting the 70 spring 49 to force said shoe against the rear face of the gear 38 and to move shaft 33 inward and again swing the guard 25 completely over the knife edge, and also over the stationary guard rod 21, thereby effectively covering the cutting portion of said edge.

From the above disclosure, it is apparent that I have provided an effective guard for fully covering the cutting portion of the 80 knife edge, as well as the upper and far portion thereof, whereby the formerly experienced dangerous accidents are substantially avoided.

While I have illustrated and described the 85 preferred form of construction for carrying my invention into effect, this is capable of variation and modification without departing from the spirit of the invention. I, therefore, do not wish to be limited to the 90 precise details of construction set forth, but desire to avail myself of such variations and modifications as come within the scope of the appended claims.

Having described my invention, what I 95 claim as new and desire to secure by Letters Patent is:

1. In a machine of the class described, having a rotatable knife, a knife guard laterally swingable over a peripheral portion of 100 said knife, and means actuated by said machine for automatically operating said guard with said machine.

2. In combination with a slicing machine having a knife, stationary and movable 105 guard means for said knife, and means actuated by said machine for automatically moving said movable guard means and exposing the slicing portion of said knife during the slicing movement of said machine. 110

3. In combination with a slicing machine having a knife, a guard for said knife, including pivoted guard means for entirely covering the slicing portion of said knife, and means operated by a driving element of 115 said machine for automatically swinging said pivoted means.

4. In combination with a slicing machine having a knife, stationary guard means for the upper, near and far portion of the knife 120 edge, additional guard means pivotally mounted for entirely covering the near portion of the knife edge, and means for automatically swinging said additional guard means.

5. In combination with a slicing machine having a knife, a guard for covering the cutting portion of the knife edge, brackets at the side of said knife, pivoting means on 130 said guard for swinging it laterally on said

brackets, and means for automatically swinging said guard means during operation of said machine.

6. In a slicing machine, in combination, 5 a knife, guard means swingable over the cutting edge of said knife, a driving shaft, and means actuated by said driving shaft for automatically swinging said guard means.

7. In a slicing machine, in combination, a 10 driving shaft, a knife having guard means, reciprocatory means for swinging said guard means, and means actuated by said driving shaft for operating said reciprocatory means.

8. In a slicing machine, in combination, a 15 rotatable knife, a movable guard for said knife, a driving shaft, means actuated by said driving shaft for moving said guard away from said knife, said actuated means including resilient means for moving said 20 guard over said knife.

9. In a slicing machine, in combination, a 25 rotatable knife, a movable guard for said knife, a driving shaft, cam means actuated by said driving shaft, and reciprocatory means actuated by said cam means for moving said guard.

10. In a slicing machine, in combination, a 30 rotatable knife, a driving shaft, a movable guard for said knife, a member actuated by said driving shaft, a cam on said member, reciprocatory means provided with an adjustable wear element actuated by said cam, and means operatively connecting said reciprocatory means and said guard.

35 11. In a slicing machine, in combination, a rotatable knife, a movable guard for said knife, a bracket, cam means mounted in said bracket, a driving shaft for said machine, means mounted on said driving shaft 40 engaging and actuating said cam means, means movably mounted in said bracket and engaged by said cam means, and means operatively connecting said movable means and said guard for moving said guard to cover 45 or uncover said knife.

12. In a slicing machine, in combination, a 50 circular knife rotatably mounted on said machine, a swingable guard for the cutting portion of the edge of said knife, a bracket mounted in said machine, a driving shaft for said machine, a member mounted on said

shaft, a rotatable member mounted in said bracket and actuated by said member, a cam on said rotatable member, a reciprocatory member mounted in said bracket, a wear 55 element adjustably mounted on said reciprocatory member being actuated by said cam, and means operatively connecting said reciprocatory member and said guard for swinging said guard over said knife edge 60 and away from said edge during the operation of said driving shaft.

13. In a slicing machine, in combination, a 65 driving shaft, a rotatable knife, a table movable toward and away from said knife, movable guard means for said knife, and means connected with and actuated by said driving shaft for automatically moving said guard means to uncover and cover said knife respectively during the to and fro motion of 70 said table.

14. In a slicing machine, in combination, a 75 rotatable knife, means for actuating said knife, a guard for said knife, including movable means for entirely covering the slicing portion of said knife, and means operated by said knife actuating means for automatically operating said movable means.

15. In a slicing machine, in combination, a 80 rotatable knife, driving mechanism for said machine and knife, stationary guard means and movable guard means for said knife, and means actuated by said driving mechanism for automatically moving said movable guard means and alternately exposing and entirely covering the slicing portion of said knife.

16. In a slicing machine, in combination, a 85 rotatable knife, stationary guard means for the upper, the near and the far portion of the knife edge, additional guard means for entirely covering the near portion of said knife edge, and means actuated by the driving mechanism of said machine for automatically operating said additional guard means.

In testimony whereof I have signed my name to this specification in the presence of two subscribing witnesses.
